JOSEPH SCHNEIBLE, OF CHICAGO, ILLINOIS; BEATRICE SCHNEIBLE-INGRAM, ADMINISTRATRIX OF SAID JOSEPH SCHNEIBLE, DECEASED, ASSIGNOR TO CLAUDE D. SCHNEIBLE, K. F. SCHREER, AND BENJAMIN B. SCHNEIDER, AS TRUSTEES UNDER THE NAME OF THE SCHNEIBLE TRUST.

ART OF DISTILLATION.

Application filed December 27, 1920. Serial No. 433,376.

The present invention relates to the art of distilling mixed liquids to effect the separation of one or more of the constituents thereof and will be fully understood from the following description, in which a preferred method of practicing the invention is set forth and illustrated by the accompanying drawings, in which:

Fig. 1 is an elevation, in part diagrammatic, illustrating in assembly apparatus for carrying out the invention;

Fig. 2 is a detail sectional view of dephlegmating plates of the distilling column;

Fig. 3 is a detail sectional view of a half of a liquid collecting and removing plate for use within the column;

Fig. 4 is a sectional view through reflux condenser plates of the distilling column;

Fig. 5 is a sectional view through the head and some of the plates of the preheater or heat exchanger, and

Fig. 6 is an elevation of a modified form of column, partially broken away.

Referring more particularly to Fig. 1 of the drawing, the numeral 10 indicates a column still, the construction of which is hereinafter described, mounted upon a suitable pedestal 11. The column still is preferably formed of sections or units, assembled in proper order upon the base or pedestal. The lowermost unit is the collection chamber 12 in which distillation residue collects before withdrawal from the column. Above this is the still chamber or unit 13, which is surmounted by a number of like units, 14, 14 forming a distilling and a dephlegmating column. At an intermediate point 15, the position of which is determined as hereinafter set forth, the liquid to be distilled is fed into the column. That portion of the column below the unit 15 may be designated as the distilling column, and the portion above as the dephlegmating column. A cut-off unit 16 may likewise be inserted at an intermediate point as hereinafter described. A reflux condensing column 17 surmounts the dephlegmating column, being formed of units or sections 18, 18 containing coils through which a cooling medium flows.

From the bonnet 19 of the column still

vapors pass through pipe 20 into the dome or bonnet 21 of the condenser 22, cooled as hereinafter described. Condensate passes off through pipe 23 and meter 24 and uncondensed vapors are drawn off through pipe 25 by a vacuum pump 26.

The residue from the column still passes out through pipe 27 and cooler 27* and is forced by pump 28 through pipe 29 into 60 a preheater 30 at an intermediate point 31. It travels upwardly through coils in the preheater, passing out at 32 through pipe 33 to cooler 34. The liquid to be treated enters the preheater through pipe 35 and descends therethrough, being heated in the portion of the preheater below the point 31 at which the residue from the still enters by means of steam admitted through pipe 36 and leaving through pipe 37. The 70 heated liquid passes from the preheater 30 through pipe 38 to the column still at the point indicated 15.

In accordance with the present invention the column still is so constructed that the 75 entire internal space thereof above the still or liquid heater proper is substantially filled with vapor and is free from accumulations of liquid. The vapor space of the column may hence be readily saturated, for example, 80 by a relatively immiscible constituent of the mixture undergoing distillation and such a constituent may accordingly be separated or returned to the residual liquid, as desired. Thus, if a liquid such as beer or 85 wine be distilled, and the column is so controlled that the constituents passing off as vapor contain more than 80% of alcohol, the higher boiling fusel oil, will readily and quickly saturate the internal space of the 90 column with its vapors. Additional fusel oil will then be returned to the residue or may be collected and removed by proper means, as more particularly hereinafter described.

A suitable construction of the column in accordance with the invention is illustrated by the detail sectional views in Figs. 2, 3 and 4 of the drawings. The units forming the dephlegmating column portion of the 100 column still may be constructed as shown in Fig. 2. The units 14 are provided at their

upper edges with external coupling flange rings 39 which form shoulders against which the lower edge of the next ring above rests. Each unit is provided internally with a centrally downwardly inclined baffle ring 40 extending inwardly from the wall of the unit. A concavo-convex plate 41 is mounted above the opening in each ring 40, upon spiral vanes 42, the lower edges of which fit upon and are secured to the upper surfaces of the baffle rings. The vanes 42 are effective in imparting a whirling movement to the vapors, and the surfaces of the deflecting plates and of the baffle rings do not permit collection or accumulation of condensed liquids.

When it is desired to remove an immiscible constituent present in a mixed liquid in small proportion, as, for example, fusel oil from beers or wines, a cut-off unit 16, so constructed as to immediately withdraw collected liquid from the column, is interposed at a suitable point in the column between two of the units or sections 14. The collecting unit 16 is provided internally with a centrally upwardly inclined collecting ring 43 which extends inwardly and is provided with an upwardly projecting flange or rim 44 at its inner edge, which extends slightly beyond the inner edge of the baffle ring 40 of the section or unit above. A pipe 45 taps the section 16 to drain the collecting ring 44 and carries the collected liquid to the receptacle 46, in which the immiscible constituent (fusel oil, for example) separates from the remainder of the liquid and may be withdrawn through valved pipe 47. From the bottom of receptacle 46 a return pipe 48 leads liquid upwardly to a point somewhat above the outlet pipe 47 and carries it into the unit 16, discharging it continuously upon the deflector plate 41 of the unit below after the proper liquid level has been established in receptacle 46. It is apparent that no accumulation of liquid upon the collecting ring 43 is possible.

In case it is not desired to collect the immiscible constituent a valved by-pass 49 is provided between the pipes 45 and 48 and valves 50 and 51 are provided in pipes 45 and 48 respectively to close them off when the by-pass is opened. With the by-pass open and valves 50 and 51 closed all liquid caught on collector-ring 43 is immediately discharged upon the next lower deflector plate, without being permitted to accumulate within the still.

The reflux condenser portion 17 of the column still is preferably made up of unit or sections 18, the construction of which is preferably as shown in Fig. 4. These units are each provided externally with a coupling flange 52 and internally with an inwardly and downwardly inclined baffle ring 53, above which is arranged a series of cir-

cular coils 54 having an inlet 55 and outlet 56, both of which pass through suitable glands in the wall of the unit. A number of depending spiral vanes 57 are secured to the baffle rings 53 (except in the case of the lowermost reflux condenser unit) and by these vanes a concavo-convex deflecting plate 58 is suspended above the coils of the next unit below. The form of the deflecting plates and baffle rings prevent accumulations of liquid and the spiral vanes 57 impart a whirling movement to the vapors and liquids. The coils in successive units may be connected together by bends 59. The units making up the body of the condenser 18 are of similar construction to the units 18 of the reflux condenser 17.

In Fig. 5 the construction of the units of the preheating device is shown. Each unit 60 is provided with a coupling flange 61, and is provided internally with a downwardly and inwardly inclined baffle ring 62. By means of brackets 63 a distributing plate 64 is supported above each baffle ring, said plate 64 being provided with a central concavo-convex portion 65, a series of openings 66 surrounding the central portion 65 and a peripheral upturned flange 67. A coil 68 is disposed in a series of spiral turns below the portion of the plate 64 containing the openings 66, the coils in adjacent units being connected by the external pipe bends 69 (shown in Fig. 1).

In order that the invention may be fully understood, it will be described in detail in connection with the distillation of a fermented liquid such as beer, consisting largely of water and containing 3 to 4% of alcohol, which is miscible in all proportions with the water, and about 0.02% of the higher fermentation product (fusel oil).

The beer to be treated passes through pipe 35 into the dome of the preheater 30, and travels downwardly therethrough, being heated in the upper portion of the preheater by residue from the still, which is forced upwardly through the coils in the preheater units and out through pipe 33. In the lower units of the preheater steam is used as a heating medium, entering through pipe 36 and leaving through pipe 37. The preheated beer leaves the preheater through pipe 38 and enters the column still at the unit marked 15.

The point of admission of the preheated beer and its temperature are carefully controlled in such manner that the operation of the column is not affected by its admission. In order to determine the proper point of admission of the beer the character of the liquid condensate within the dephlegmating column is determined at various points, and that point is selected for the admission of the beer at which the liquid condensate has substantially the same

composition or alcohol concentration as the beer. In general, this point may be determined by temperature and pressure observations, as the temperature at any point

- 6 within a column constructed in accordance with this invention is substantially the boiling point of the liquid at that point. The temperature of the preheated beer is brought to substantially the temperature in the column at the point of introduction or not more than 0.5 to 1° C. above or below it by control of the supply of steam to the preheater. The temperature of the beer leaving the preheater is maintained at this
- 10 point, a temperature control line 70 from the beer line 38 controlling the steam admission valve 71 on steam line 36 through a suitable control device 72.

When the preheated beer enters the column it immediately becomes subject to the conditions prevailing therein, and by reason of the conditions of its admission, as hereinbefore stated, the operation of the column is not affected. The still or heater unit, 20 at the base of the still, is heated by steam entering through pipe 73, its outlet being through pipe 74. In order to maintain the proper conditions within the column the admission of steam is controlled to maintain a substantially constant temperature at an intermediate point in the distilling column of the column still above the heater and above the point at which ebullition occurs, the controlling thermostat being at 30 that point substantially constantly laved by the descending liquids in the dephlegmating column. The numeral 75 indicates the line from the thermostat which actuates control device 76 to control the steam admission valve 77. A recording thermometer 78 indicates and records the temperature prevailing at the point of control.

The temperature of the vapors escaping from the top of the column still are maintained constant by suitable control of the flow of cooling medium, for example, cold water, to the coils of the reflux condenser which forms the top of the column still. This may be effected by controlling the supply valve 78 on the supply line 79 by means of the control device 80, governed by thermostat line 81 running to the interior of the bonnet 17 of the column. The cooling medium (water) may be supplied directly to the reflux condenser from a suitable source, or it may be forced, for example, by pump 82 upwardly through the coils in alcohol condenser 22, then through line 79 controlled by valve 78 into and downwardly through the coils of the reflux condenser 17. An inverted U-trap 83 in the exit line 82 maintains the liquid level in the cooling coils. The quantity of cooling medium required by the reflux condenser 17 is in excess of that required by the

alcohol condenser 22, and hence the latter is provided with an ample supply when the feed of cooling medium is controlled in accordance with the requirements of the reflux condenser.

70

The vapor passages in the column are constructed of ample size to permit the free passage of the ascending vapors, which are concentrated to 80% alcohol (by volume in the condensed liquid) or higher. The fusel oil vapors soon saturate the interior space of the column, and, if not collected by means of the cut-off plate 16 at a point in the column where the concentration is about 47% alcohol by volume in the condensed liquid, or slightly thereabove as hereinbefore described, are returned to the residue which leaves the still through pipe 27. The decrease in temperature through the column is regular and uniform and the temperature prevailing at any point therein is substantially the boiling point of the liquid reflux at that point. The proper point for the insertion of the cut off plate may hence be readily determined in practice by temperature observations.

75

The desired absolute pressure throughout the device may be maintained by any suitable means, for example, the exhaust pump 26 connected to the vapor space in the lower portion of the condenser 22. Two lines connecting the pump 26 with the vapor pipe 25 are provided, one, 84, being provided with a valve 85 of ordinary construction and the other 86 with a variable pressure check valve 87 by adjusting which the vapor pressure within the system may be readily controlled. In order to bring the system to the desired pressure conditions on starting the valve 85 may be opened, and when the working pressure is established the valve 85 is closed and the valve 87 may be adjusted from time to time to maintain the working pressure.

80

The pressure drop or gradient through the column is regular and uniform and is maintained at a point sufficiently low to prevent carrying liquid reflux upwards through the column. In general, the operating conditions are so maintained that the pressure drop from the base of the column to the point where the alcohol vapors are removed is not greater than $\frac{3}{4}$ inch of mercury.

85

To illustrate the working conditions prevailing in the system during operation, with an absolute pressure of about 2.7 pounds per square inch at the top of the column and a condensate from the condenser 22 of 95% alcohol by volume, the pressure at the bottom of the column is 3 lbs. absolute per square inch, the temperature maintained at the still control point 75^a is about 60° C., that at the bonnet 19 of the column still is about 39° C. and that prevailing at the point 15 where the beer is introduced is 125 180

about 59° C. The beer leaving the preheater is maintained at about this temperature. The pressure at the heater of the still is about 3.1 lbs. absolute pressure per square

5 inch.

In Figure 6 I have shown a modified form of construction of a column still in accordance with my invention, wherein means are provided in a single column for the production, rectification and withdrawal of the desired products of fractional distillation. In that figure, numeral 91 indicates a heater unit, through which the heating medium, such as steam, is supplied through pipe 92 and from which the heating medium is withdrawn through pipe 93. Below the heater unit 91 is provided a unit 94 in which the residue of the distillation operation collects and from which it is withdrawn through pipe 95. The heater unit 91 is surmounted by a number of dephlegmating units 14 forming a distilling column 96 and a dephlegmating column 97. Between the distilling column 96 and the dephlegmating column 97 a feed unit 15 is interposed, into which fresh liquid is supplied through pipe 98. The fresh liquid is preheated in accordance with the foregoing description of my process to a temperature substantially the same as the temperature within the column at the point at which it is supplied, this point being that at which the reflux liquid within the column has approximately the same composition as the fresh liquid supplied. At an intermediate point in the dephlegmating column 97, above the feed unit 15, a cut-off plate 16 may be interposed. The liquid collected in this plate is immediately withdrawn through pipe 99 into the receptacle 100, where a separation of any immiscible constituent may take place. The separated immiscible constituent may be removed through discharge pipe 101 and the remaining liquid returned through pipe 102 to the cut-off unit. A by-pass 103 is provided between the pipes 99 and 102 for use in case it is not desired to effect the separation of an immiscible constituent.

Above the dephlegmating section 97 is a reflux condenser section 104, made up of reflux condenser plates 18, 18. At the top of the reflux condenser section is a cut-off unit 105, of construction similar to that of cut-off unit 16, and the liquid collected therein is drained off through pipe 106 and cooling coil 107 to a suitable receptacle (not shown). Above the cut-off plate 105 are placed a series of reflux condenser plates 18, 18, forming a rectifying section 108, at the top of which a cut-off plate 109 is inserted and the liquid collected there may be withdrawn through pipe 110 and cooling coil 111 to a suitable receptacle (not shown). Above the cut-off unit 109 an additional rectifying condenser 108^a may be placed, if

desired. The column is surmounted by a dome 112, which is provided with a vapor outlet 113, to which may be applied an exhaust pump, if desired.

A cooling medium is supplied through pipe 114 to the uppermost unit of the rectifying section 108^a, and descends through the coils therein, leaving through pipe 114^a. A cooling medium is likewise supplied through pipe 120^a to the uppermost unit of the rectifying condenser 108, and descends through the coils in the units of the rectifying and refluxing sections 108 and 104 to the lowermost unit thereof, out of which it passes through the inverted U-shaped pipe or trap 116, the highest point of which is slightly above the uppermost cooling coil in the top unit of the rectifying section 108 of the column. A full column of cooling liquid in the coils is thereby assured.

The supply of heating medium to the heater unit 91 is controlled by means of valve 117 and control device 118 to produce a constant temperature at a point in the distilling section 96 of the column below the point of introduction of fresh liquid as described in connection with the form of construction of Fig. 1. The supply of cooling medium to the rectifying and reflux condenser sections of the column are, controlled by valve 120 and control device 121 to produce a constant temperature of the vapors in the column at the unit 105 where rectified liquid is withdrawn therefrom.

In operating the column, for example, for the distillation of beer or wine, the fresh beer is introduced into the column through pipe 98 at the feed unit 15 and descends through the distilling section 96 together with refluxed liquid. The vapors ascend through the column, in which, as has been hereinbefore stated, no accumulation of refluxing liquid is permitted. If it is desired to remove fusel oil, this may be accomplished by means of the cut-off unit 16 as described in connection with the form of construction shown in Figure 1. The operation of the reflux condenser section 104 is controlled to produce a temperature in the column at the cut-off plate 105, such that the liquid collected there is alcohol of the desired concentration, for example, 190 proof. This control is effected by means of the control device 121, as above described. The liquid withdrawn at the unit 105 is substantially pure, being rectified by the action of the rectifying section 108 superposed upon it. If it is desired to recover the heads or lower boiling point products, this may be effected by means of the cut-off unit 109, by means of which the heads may be withdrawn, having been previously rectified in the column. At the cut-off plates 105 and 109 the liquids are withdrawn at substantially their boiling points and are consequently

passed through cooling coils before passing into the receiving vessels. The construction of the column units and their operation, as herein described in detail, results in a marked uniformity of operation of the column, there being a very regular drop in temperature and also a very regular decrease in pressure throughout the column. The operating conditions are so controlled that this drop in pressure is not sufficient to cause liquid reflux to be carried through the column, and is preferably maintained below three-fourths of an inch between the cut-off plate 105 and the heater unit.

The specific details of operation and construction which have been set forth are not intended to be regarded as limitations upon the scope of the invention except in so far as included in the accompanying claims.

I claim:

1. In a distilling apparatus, a unitary column construction comprising superposed heating, distilling and reflux condensing sections, means for supplying a heating medium to the heater section, means for supplying a cooling medium to the reflux condensing section, means for regulating the supply of heating medium to the heater section by means of temperature indications in the distilling section, and means for regulating the supply of cooling medium to the reflux condensing section by the temperature of the vapors issuing therefrom.

2. In a distilling apparatus, a unitary column construction comprising superposed heating, distilling and reflux condensing sections, means for supplying a heating medium to the heater section, means for supplying a cooling medium to the reflux condensing section, and means for regulating the supply of heating medium to the heater section by means of temperature indications in the distilling section.

3. In a distilling apparatus, a unitary column construction comprising superposed heating, distilling and reflux condensing sections, means for supplying a heating medium to the heater section, means for supplying a cooling medium to the reflux condensing section, means for regulating the supply of heating medium to the heater section by means of temperature indications in the distilling section, and means for controlling the pressure of exhaust of uncondensed gases from said column.

4. In a distilling apparatus, a unitary column construction comprising superposed heating, distilling, dephlegmating and reflux condensing sections, means for supplying a heating medium to the heating section thereof, means for controlling the supply of cooling medium to the reflux condensing section by the temperature of vapors issuing therefrom, and means for controlling the pressure of exhaust of vapors from the column.

5. In a distilling apparatus, a unitary column construction comprising superposed heating, distilling, dephlegmating and reflux condensing sections, means for supplying a heating medium to the heating section, means for supplying a cooling medium to the reflux condensing section, means for controlling the supply of heating medium to the heating section by temperature indications in the distilling section, means for controlling the supply of cooling medium to the reflux condensing section by the temperature of the vapors issuing therefrom, and means for regulating the pressure of exhaust of uncondensed vapors from the column.

6. In a distilling apparatus, a unitary column construction comprising superposed heating, distilling and reflux condensing sections, said sections being constructed to provide a continuous, uninterrupted vapor passage, means for supplying a heating medium to the heater section, means for supplying a cooling medium to the reflux condensing section, means for regulating the supply of heating medium to the heater section by means of temperature indications in the distilling section, and means for regulating the supply of cooling medium to the reflux condensing section by the temperature of the vapors issuing therefrom.

7. In a distilling apparatus, a unitary column construction comprising superposed heating, distilling and reflux condensing sections, said sections being constructed to provide a continuous, uninterrupted vapor passage, means for supplying a heating medium to the heater section, means for supplying a cooling medium to the reflux condensing section, and means for regulating the supply of heating medium to the heater section by means of temperature indications in the distilling section.

8. In a distilling apparatus, a unitary column construction comprising superposed heating, distilling and reflux condensing sections, said sections being constructed to provide a continuous, uninterrupted vapor passage, means for supplying a heating medium to the heater section, means for supplying a cooling medium to the reflux condensing section, means for regulating the supply of heating medium to the heater section by means of temperature indications in the distilling section, and means for controlling the pressure of exhaust of uncondensed gases from said column.

9. In a distilling apparatus, a unitary column construction comprising superimposed heating, distilling, dephlegmating and reflux condensing sections, said sections being constructed to provide a continuous, uninterrupted vapor passage, means for supplying a heating medium to the heating section thereof, means for controlling the pressure of exhaust of vapors from the column.

supply of cooling medium to the reflux condensing section by the temperature of vapors issuing therefrom, and means for controlling the pressure of exhaust of vapors from the column.

10. In a distilling apparatus, a unitary column construction comprising superposed heating, distilling, dephlegmating and reflux condensing sections, said sections being constructed to provide a continuous, uninterrupted vapor passage, means for supplying a heating medium to the heating action, means for supplying a cooling medium to the reflux condensing section, means for controlling the supply of heating medium to the heating section by temperature indications in the distilling section, means for controlling the supply of cooling medium to the reflux condensing section by the temperature of the vapors issuing therefrom, and means for regulating the pressure of exhaust of uncondensed vapors from the column.

11. In a distilling apparatus, a unitary column construction comprising superposed heating, distilling and reflux condensing sections, said sections being constructed to provide a continuous uninterrupted vapor passage, means for supplying a heating medium to the heating section, means for supplying cooling medium to the reflux condensing section and means for imparting rotating motion to the vapors in said vapor passage.

12. In a distilling apparatus, a unitary column construction comprising superposed heating, distilling and reflux condensing sections, said sections being constructed to provide a continuous uninterrupted vapor passage, means for supplying a heating medium to the heating section, means for supplying cooling medium to the reflux condensing section and means for imparting rotating motion to the vapors in said vapor passage, means for regulating the supply of heating medium to the heating section by temperature indications in the distilling section, and means for controlling the supply of cooling medium to the reflux condensing section by the temperature of vapors issuing therefrom.

13. In a distilling apparatus, a unitary column construction comprising superposed heating, distilling, dephlegmating and reflux condensing sections, said sections being constructed to form a continuous, uninterrupted vapor passage through the column, means for producing a gradual temperature decrease from the heating section through the reflux condensing section of the column, and means for withdrawing reflux from said column without interrupting the vapor passage therethrough.

14. In a distilling apparatus, a unitary column construction comprising superposed

heating, distilling, dephlegmating and reflux condensing sections, said sections being constructed to form a continuous, uninterrupted vapor passage through the column, means for supplying a heating medium to the heating section, means for supplying a cooling medium to the reflux condensing section, means for controlling the supply of heating medium to the heating section by temperature indications in the distilling section, means for controlling the supply of cooling medium to the reflux condensing section by the temperature of the vapors issuing therefrom, and means for withdrawing reflux from said column without obstructing the vapor passage therethrough.

15. In a distilling apparatus, a unitary column construction comprising superposed heating, distilling, dephlegmating and reflux condensing sections, means for supplying heating medium to the heating section, means for supplying a cooling medium to the reflux condensing section, means for controlling the supply of heating medium to the heating section by temperature indications in the distilling section, means for controlling the supply of cooling medium to the reflux condensing section by the temperature of vapors issuing therefrom, means for feeding fresh liquid into the column at a point in the column where the composition of refluxed condensate has approximately the same composition as the fresh liquid, and means for withdrawing residue from the still.

16. In a distilling apparatus, a unitary column construction comprising superposed heating, distilling, dephlegmating and reflux condensing sections, means for supplying heating medium to the heating section, means for supplying a cooling medium to the reflux condensing section, means for controlling the supply of heating medium to the heating section by temperature indications in the distilling section, means for controlling the supply of cooling medium to the reflux condensing section by the temperature of the vapors issuing therefrom, means for preheating fresh liquid, means for introducing the preheated fresh liquid into the column at a point where the refluxed condensate has approximately the same composition as the fresh liquid, and means for withdrawing residue from the heating section.

17. In a distilling apparatus, a unitary column construction comprising superposed heating, distilling, dephlegmating, reflux condensing and rectifying sections, means for supplying cooling medium to the reflux condensing and rectifying sections, means for controlling the supply of cooling medium thereto by the temperature at the top of the reflux condensing section, and means for withdrawing from the top of the re-

- flux condensing section condensate formed in the rectifying section.
18. In a distilling apparatus, a unitary column construction comprising superposed heating, distilling, dephlegmating, reflux condensing and rectifying sections, said sections being constructed to form an uninterrupted vapor passage through the column, means for supplying a cooling medium to the rectifying and reflux condensing sections, means for controlling the supply of cooling medium by the temperature of the vapors at the top of the reflux condensing section, and means for withdrawing condensate formed in the rectifying section from the top of the reflux condensing section without interrupting the vapor passage through the column.
19. In a distilling apparatus, a unitary column construction comprising superposed heating, distilling, dephlegmating, reflux condensing and rectifying sections, said sections being constructed to provide an uninterrupted vapor passage through the column, means for supplying cooling medium to the reflux condensing section, means for controlling said supply of cooling medium by the temperature of the vapors of the top of the reflux condensing section, means for controlling the pressure of exhaust of uncondensed gases from the column, and means for withdrawing from the top of the reflux condensing section liquid condensate formed in the rectifying section.
20. In a distilling apparatus, a unitary column construction comprising a superposed heating, distilling, dephlegmating, reflux condensing and rectifying sections, said sections being constructed to provide an uninterrupted vapor passage through the column, means for supplying a heating medium to the heating section, means for controlling said supply of heating medium by temperature indications in the distilling section, means for supplying cooling medium to the reflux condensing section, means for controlling said supply of cooling medium by the temperature of vapors at the top of the reflux condensing section, means for controlling the pressure of uncondensed gases exhausted from the column, and means for withdrawing from the top of the reflux condensing section liquid condensate formed in the rectifying section without interrupting the vapor passage through the column.
21. In combination, a column still, the internal construction of which is such as to provide an uninterrupted vapor passage therethrough, means for supplying heating mediums only to the base of the column, means for supplying a cooling medium in the upper part of the column, means for controlling the pressure of uncondensed gases exhausted from the column and means for controlling the heating and cooling me-
- diums by temperature indications within the still to control the pressure drop in the column still.
22. In combination, a distilling system including a unitary column construction comprising superposed heating, distilling, dephlegmating and reflux condensing sections, means for supplying a heating medium to the heating section, means for supplying a cooling medium to the reflux condensing section, means for exhausting uncondensed gas and vapor from the system and means for controlling the pressure drop in the column including means for controlling the supply of heating medium to the heating section and of cooling medium to the reflux condensing section by temperature indications within the column.
23. In a distilling apparatus, a unitary column construction comprising superposed heating, distilling, dephlegmating and reflux condensing sections, the construction of said sections being such as to provide a continuous vapor passage through the column, means for supplying a heating medium to the heating section, means for supplying a cooling medium to the reflux condensing section, means for controlling the pressure of exhaust of uncondensed vapors from the column, and means for controlling the pressure drop in the column to produce a pressure drop of not over three-fourths inch between the heating section and the top of the reflux condensing section, said means including means for controlling the supply of heating medium to the heating section and of cooling medium to the reflux condensing section by temperature indications within the column.
24. In a distilling apparatus, a unitary column construction comprising superposed heating, distilling, dephlegmating and reflux condensing sections, a condenser for condensing vapors issuing from the reflux condensing section, means for controlling the pressure of uncondensed vapors issuing from the condenser, and means for controlling pressure drop within the column structure comprising means to control the temperature conditions therein.
25. The process of continuously distilling a liquid mixture which comprises heating a liquid mixture, conducting the evolved vapors in a continuous rising body, cooling the rising vapor body to condense fractions thereof, exhausting uncondensed gases from the rising vapor body, controlling the pressure of uncondensed gases exhausted from the column of vapor and controlling the pressure drop in the vapor body by controlling the heating of the liquid mixture and the cooling of the vapor body.
26. The process of continuously distilling a liquid mixture which comprises heating a liquid mixture, conducting the evolved

vapors in a continuous rising body, cooling the rising body to condense fractions thereof, removing condensed fractions of desired compositions without interrupting the continuity of the vapor body, exhausting uncondensed gases from the column of vapor, controlling the pressure of uncondensed gases exhausted from the column of vapor and producing a predetermined pressure drop in the vapor body by controlling the heating of the liquid mixture and the cooling of the vapor body.

27. The process of continuously distilling a liquid mixture which comprises heating a liquid mixture, conducting the evolved vapors in a continuously rising body and imparting a rotating motion thereto, cooling the rising vapor body to condense fractions thereof, exhausting uncondensed gases from the column of vapor, controlling the pressure of uncondensed gases exhausted from the column of vapor, and controlling the pressure drop in the vapor body by controlling the heating of the liquid mixture and the cooling of the vapor body.

28. The process of continuously distilling

a liquid mixture which comprises heating a liquid mixture, conducting the evolved vapors in a continuous rising body, cooling the rising vapor body to condense fractions thereof, withdrawing and condensing vapors from the column of rising vapor maintaining a controlled exhaust pressure on the uncondensed gases, and controlling the pressure drop in the vapor body by controlling the heating of the liquid mixture and the cooling of the vapor body.

29. The process of continuously distilling a liquid mixture which comprises heating a liquid mixture, conducting the evolved vapors in a continuous rising body and imparting a rotating motion thereto, cooling the rising vapor body to condense fractions thereof, withdrawing and condensing vapors from the column of rising vapor, maintaining a controlled exhaust pressure on uncondensed gases, and controlling the pressure drop on the vapor body by controlling the heating of the liquid mixture in the cooling of the vapor body.

JOSEPH SCHNEIBLE.

- vapors in a continuous rising body, cooling the rising body to condense fractions thereof, removing condensed fractions of desired compositions without interrupting the continuity of the vapor body, exhausting uncondensed gases from the column of vapor, controlling the pressure of uncondensed gases exhausted from the column of vapor and producing a predetermined pressure drop in the vapor body by controlling the heating of the liquid mixture and the cooling of the vapor body.
27. The process of continuously distilling a liquid mixture which comprises heating a liquid mixture, conducting the evolved vapors in a continuously rising body and imparting a rotating motion thereto, cooling the rising vapor body to condense fractions thereof, exhausting uncondensed gases from the column of vapor, controlling the pressure of uncondensed gases exhausted from the column of vapor, and controlling the pressure drop in the vapor body by controlling the heating of the liquid mixture and the cooling of the vapor body.
28. The process of continuously distilling a liquid mixture which comprises heating vapors in a continuous rising body, cooling the rising vapor body to condense fractions thereof, withdrawing and condensing vapors from the column of rising vapor maintaining a controlled exhaust pressure on the uncondensed gases, and controlling the pressure drop in the vapor body by controlling the heating of the liquid mixture and the cooling of the vapor body.
29. The process of continuously distilling a liquid mixture which comprises heating vapors in a continuous rising body and imparting a rotating motion thereto, cooling the rising vapor body to condense fractions thereof, withdrawing and condensing vapors from the column of rising vapor, maintaining a controlled exhaust pressure on uncondensed gases, and controlling the pressure drop on the vapor body by controlling the heating of the liquid mixture in the cooling of the vapor body.

JOSEPH SCHNEIBLE.

Certificate of Correction.

It is hereby certified that in Letters Patent No. 1,587,188, granted June 1, 1926, upon the application of Joseph Schneible, of Chicago, Illinois, for an improvement in "The Art of Distillation," errors appear requiring correction as follows: In the grant and in the heading to the printed specification, assignment, name of second-mentioned assignee, for "K. F. Schrerer" read *K. F. Schreier*, as shown by the records of assignments in this office; and that the said Letters Patent should be read with these corrections therein that the same may conform to the record of the case in the Patent Office.

Signed and sealed this 17th day of August, A. D. 1926.

[SEAL.]

M. J. MOORE,
Acting Commissioner of Patents.
